assigns

Samuel W. Gillett of Albany, N.Y.
assigns to the U.S. Patent Office, dated May 15, 1866
Design for the Plates of a Cork-Stone.

The undersigned is willing to make and furnish for the use of the inventor
any number of copies of the design for the plates of a cork-stone.

He will do so at his own expense.

Bent knows that Samuel W. Gillett of the City and County
of Albany and State of New York has invented or produced a new and original
design for the plates of a cork-stone; and to witness declare the following
is a full and exact description of the same, reference being made to the
accompanying photographs.

A represents the design for side door.

B . . . . . front.

D.F. . . . . over door.

E . . . . . end facade.

Together forming plates for cork-stone "front."

I claim as new and desire to secure by Letters Patent, the
design or plan of the cork-stone, as shown and described.
